UNITED STATES PATENT OFFICE.

FRANK J. KAEHNI AND WILLIAM L. KAEHNI, OF CLEVELAND, OHIO, ASSIGNEES TO THE CLEVELAND TRUST COMPANY, TRUSTEE, OF CLEVELAND, OHIO, A CORPORATION OF OHIO.

SOUND-PRODUCING DEVICE.

Application filed October 9, 1924. Serial No. 748,683.

The principal object of this invention is to produce a simple effective magnetic device for use in combination with the reproducer mechanism of a phonograph and responsive to variations in electric current through the device, to thus produce sound by the consequent actuation of the reproducer diaphragm, the connection between the reproducer mechanism and the magnetic device being preferably through the usual needle of the phonograph.

The present invention constitutes an improvement upon the inventions directed to the same purpose and shown, described and claimed in the prior application of Frank J. Kaehni and Wm. L. Kaehni, No. 561,415 filed May 16, 1922, and Patent No. 1,426,743 granted August 22nd, 1922 to said Kaehni and Kaehni.

Among other objects of the improvements of the present application is the accomplishment of re-production of comparatively large volume of sound while obtaining a sweet true quality, due to more accurate and faithful reproduction of the variations of current through the magnetic device.

More specific objects include the arrangement of the device in a compact form that it may easily be placed in the proper position on standard types of phonographs at the side of the record carrying table or on the record carrying table, in a position to receive the needle of the phonograph without requiring any change in the reproducer parts.

In carrying out our present invention, we prefer to utilize a vibrating member in the nature of a reed of magnetic material responsive to a weak magnetic field. It reaches higher magnetic density for given amount of electrical energy creating the magnetic field than materials usually used. That is, it becomes more magnetic in a given magnetic field than soft iron or silicon iron. A material found very suitable for our present purpose is an alloy of 44% nickel and 56% iron. The use of this material in such fields forms the subject matter of an application of Zay Jeffries, filed October 6, 1924, Serial No. 742,078.

Other objects and advantages of the present invention will become apparent from the following specification and the essential

characteristics are summarized in the appended claims.

In the drawings Fig. 1 is a perspective view of our device showing the connecting parts of the reproducer, stylus, and needle in normal operating position; Fig. 2 is a perspective view showing the casing of the device removed; Fig. 3 is a plan of the same; Fig. 4 is a bottom plan; Fig. 5 is a vertical transverse section on an enlarged scale; Fig. 6 is a similar section at right angles with Fig. 5, the planes of these sections being indicated by the correspondingly designated lines of Fig. 3; Fig. 7 is a sectional detail also enlarged showing the manner of connecting the internal coil with lead wires.

The device as shown consists primarily of a base on which is mounted a magnet of particularly adapted construction, and an electromagnetic coil through the core of which passes a vibrating member spaced apart from the surrounding member and projecting between the poles of the magnet. The base portion is indicated at 10 and is provided with a downwardly extending flange forming a rest. At the center is an upwardly projecting spool preferably integral therewith and having a flange 12 at the upper end thereof, thereby confining wires of the coil indicated at 15. The center portion 11 of the spool is hollow and through it projects the vibrating member 20.

This vibrating member or reed is shown as mounted on the base by means of a flat spring 22 to which the reed is secured as at 23 and the ends of this spring are provided with openings through which protrude screws 24 shown as threaded into bushings 25 mounted in the base. The bushings are to provide suitable thread engagement as the base element is preferably formed of non-conducting material such as bakelite.

The equivalent of a horse shoe magnet is formed by semi-circular members 32 spaced upwardly from the base by one or more stampings, as shown, and the ends of these members are clamped between shims indicated at 30 and the sector-shaped pole pieces 35, through which pass the screws 36 threaded into bushings 37 in the base. It will be noted that in place of the semi-circular members 32, we may provide complete laminated rings if desired, but we have

found that better contact between the laminations is attained by making the parts as shown.

As shown in Figs. 2 and 3, the sector pole pieces 35, present flattened faces 38 to flat surfaces 21 of the reed 20 normally standing slightly spaced apart therefrom to allow for the vibration movement and yet securing closest proximity to assure maximum magnetic action. The pole pieces 35 have the openings for the screw 36 slightly enlarged to allow adjustment of the air gap between them and the reed. The ends of the wire of the coil 15 are led to binding screws indicated at 40, Figs. 4 and 7, the coil wire being indicated in Fig. 7 at 15^a. A pair of suitable cords commonly termed "phone cords", designated 45, have their binding clips clamped under the heads of the screws 40. These cords, of course, are adapted to lead the pulsating or variable audio-frequency current to the coil 15, one of the most usual uses being to connect them in circuit with a suitable audion of a radio receiving apparatus.

In order to strengthen the magnetic field through the reed, we prefer to form the spring portion 22 of a ferromagnetic conductor and similarly the screws 24 are of like material, and as shown, they may protrude upwardly to a point adjacent the ring members forming the base of the magnet. The poles are intermediate the two upwardly projecting screws and a magnetic flux circuit is created through the reed, poles 35 and base rings, returning across a slight air gap to the screw members 24 and through the spring member 22 to the reed. Thus a flux circuit is formed through the poles and base portions of the magnet through a neutral point, at the screws, to the other end of the reed. This intensifies the magnetic action upon the reed, although it is not vital to the operation of the device.

The reed as indicated above, is responsive to a very weak magnetic field, and of course, when the coil 15 is energized, the reed becomes a magnetic bar, so that as the current through the coil 15 is varied, the magnetic strength of the reed is correspondingly varied, and it is attracted and repelled by the pole pieces 35. Thus we have a variable magnetic strength in the reed which reacts with the strength of the permanent magnetic field to cause it to move alternately toward and away from each pole in true synchronism with the variations in the current through the coil. This vibration accordingly is an exact reproduction of the current input and the phonograph needle resting in the notch or groove 50 in the upper end of the reed is positively moved, very similarly to the movement given it by a record. Therefore, the electrical energy being translated into transverse vibrations of the reed

is mechanically and positively transmitted to the phonograph diaphragm producing the sound vibrations in the reproducer box and phonograph horn.

It is essential that in combining this device with the usual reproducer of a phonograph that it be so positioned as to cause a vibration of the phonograph needle transversely of the plane of the phonograph diaphragm. When the needle is placed in the notch or groove 50, it is quite natural to point this groove parallel with the reproducer diaphragm holder. However, if the result is not satisfactory, it is equally natural for one operating radio receiving sets and the like to turn the device slightly on its base until the best results are obtained, after the manner of adjusting the dials of the receiving set. If desired, indications may be made to assist in accurately positioning it.

The magnet and reed are preferably enclosed except for the upper end of the reed in a cup shaped casing 60, shown as resting upon an offset shoulder on the base and positioned by the cylindrical portion shown above the shoulder. The top of the cap or cup preferably has a depression allowing it to rest upon the magnet pole pieces to which it may be clamped by screws 62 threaded into the pole pieces 35, as shown. This affords a convenient means for the location of a suitable name plate, indicated at 65. The base is preferably closed by a disc 70 having felt or any suitable facing indicated at 72 to avoid marring the surface on which it may be placed. This is held in position by screws 74 being threaded into the bushings 37 the screw heads engaging upwardly beveled flanges surrounding the openings for the screws, in order that the heads of the screws may be above the surface on which the device rests.

We claim:

1. The combination with a phonograph reproducer having a rockable stylus and sound reproducing diaphragm, and a magnetic device responsive to audio-frequency variations in an electric circuit and consisting of a base member, and a permanent magnet of flat arcuate pieces, pole members secured thereto to form in effect with the said pieces a continuous magnetic annulus and extending inwardly from such annulus, a vibrating member between the poles, an electromagnetic coil for subjecting the vibrating member to variable magnetic flux, said vibrating member adapted to be connected with the rockable stylus.

2. The combination with the usual reproducing mechanism of a phonograph including the stylus, of a means for translating variable electric current into mechanical vibrations including a vibrating member adapted to be connected to cause positive vibration of the stylus, a laminated magnet

- having arcuate portions surrounding said member and surmounted by inwardly projecting flat pole pieces, a base member having a hollow upward projection through which said vibrating member extends, means for resiliently mounting a vibrating member on the base, an electromagnetic coil on said projection, and means for supplying a variable current to the coil.
3. In a sound reproducing device, the combination with a phonograph reproducer having a diaphragm, a needle engaging and positioning means and a means for translating variations of an electric current into mechanical vibrations in said phonograph diaphragm including a base member of non-magnetic material having the spool formed thereon, an electromagnetic coil on said spool formed thereon for creating a variable magnetic field responsive to variations in said current, a magnetic reed projecting through said spool and mounted to vibrate therein, a permanent magnet surrounding the spool, the body of the magnet consisting of flat ring members, and flat pole pieces secured thereto and projecting inwardly to points adjacent the one end of the reed.
4. A device for actuating the reproducer of the phonograph to produce sound including a vibrating member responsive to variations in an electric current and having a non-magnetic base member formed with an upwardly projecting spool, a coil carried by the spool and a permanent magnet consisting of flat laminations surrounding the spool and flat pole pieces projecting inwardly over said coil, and a vibrating magnet comprising an armature projecting through the spool and to a point adjacent the pole pieces, a resilient means disposed substantially at right angles to the vibrating member and secured to the base for carrying the vibrating member, said vibrating member having the property of becoming more magnetic in a given weak field than soft iron or silicon iron.
5. In a sound producing device, the combination of the reproducer mechanism of a phonograph consisting of a base adapted to rest on the record table or at the side thereof and formed of non-metallic material and having a hollow spool rigid therewith, an electromagnetic coil on said spool, a permanent magnet consisting of arcuate punchings of flat magnetic metal secured to the base around said coil, sector-shaped pole pieces adjustably secured upon said arcuate pieces and projecting inwardly, and a vibrating member adapted to be variably magnetized by said coil and reacting toward and away from the poles of the permanent magnet.
6. In a device for translating variations in an electric current into mechanical vibrations, the combination of an electromagnet, a non-magnetic core and base supporting the same, an arcuate permanent magnet mounted above the base, a coil within the magnet, a reed projecting loosely through the coil and acted upon by the field of said coil, a support for the reed of resilient ferromagnetic material and securing means therefor of similar material projecting through the base to a point adjacent the permanent magnet to form a magnetic flux circuit through the reed and permanent magnet.
7. A magnetic sound producing device adapted to actuate the usual stylus of a phonograph having a sound producing mechanism with a vertical sounding diaphragm consisting of a base member, a magnetic coil with a hollow center and a vibrating reed projecting upwardly through said coil, a magnet having a body portion surrounding the coil and having pole pieces adjacent the reed, a casing surrounding the magnet and fitted to the base, said casing having two of its sides beveled to clear the lower edge of the phonograph sound box when the phonograph needle is resting upon said vibrating member, the base being adapted to rest upon a record carrying table or on a phonograph casing at the side thereof.
8. A magnetic sound producing device adapted to coact with a phonograph sound box or the like, including a base and a vibrating member, a magnetic coil subjecting the vibrating member to a magnetic flux, a permanent magnet having its pole pieces adjacent the vibrating member and having its body portion annular and surrounding the coil, a resilient support for the vibrating member of ferromagnetic material constituting a bridge member beneath the base, securing screws therefor, projecting upwardly toward the magnet body, each at a point remote from the pole pieces.

In testimony whereof, we hereunto affix our signatures.
